UNITED STATES PATENT OFFICE.

WILLIAM S. PROUDFIT, OF GRAND RAPIDS, MICHIGAN.

LOOSE-LEAF BINDER.

1,224,664.

Specification of Letters Patent. Patented May 1, 1917.

Application filed May 27, 1915. Serial No. 30,789.

To all whom it may concern:

Be it known that I, WILLIAM S. PROUDFIT, a citizen of the United States, residing at Grand Rapids, in the county of Kent and State of Michigan, have invented new and useful Improvements in Loose-Leaf Binders, of which the following is a specification.

The present invention relates to loose-leaf binders, and its object is generally, to provide an improved device of that character; and more particularly, such a device having improved adjusting means for the leaf-holding members; and further, such a device having improved means for holding such members in adjusted position.

These and any other objects appearing hereinafter are attained by, and the invention finds preferable embodiment in, the structures hereinafter described and illustrated by the accompanying drawings, in which:—

Figure 1 is a plan view of the inside of the opened covers of a loose-leaf binder containing leaves;

Fig. 2 is a view in perspective of a clip for adjustably connecting a leaf-holding member to a cross bar;

Fig. 3 is a like view of a portion of a cover of such a binder, showing a guide for a leaf-holding member; and a bearing for a rotatable clamp for such a member;

Fig. 4 is a like view of a form of such clamp;

Fig. 5 is a cross section of the same taken on line 5—5 of Fig. 4; and

Fig. 6 is a view in perspective of another form of such clamp.

In the embodiment of my invention chosen for illustration by the drawings and for detailed description in the body of this specification, the covers 1 and 2 are connected by flexible leaf-holding members which are preferably resilient, as the flat steel springs 3 carrying the leaves 4. Said members are adjustable on the cover 2 to different thicknesses of the leaf body, by sliding them longitudinally in guides 5 near the binding edge of the cover, and holding them in adjusted position by means carried by said cover and comprising a rotatable shaft 6 having an eccentric cam 7 adapted in one rotary position of the shaft to clamp said member in its adjusted position, as by engaging it directly and clamping it to such cover. This cam may be formed by

flattening a portion of the shaft to the shape shown in Fig. 4.

In Figs. 1 and 4, the shaft has a handle portion 8 adapted in the shaft's clamping position to overlie the free end of said member and hold it against or in parallel relation to the cover at a distance from the point of the clamping action thereon.

In Fig. 6, the shaft is continuous and carries cams for clamping all the leaf-holding members by one operation.

A rotary bearing for said rotatable shaft is died up from said cover and comprises two portions; a portion 10 forming the inner side of such bearing (next the cover), 70 and another portion 11 forming the outer side of such bearing. Other portions are died up from the cover to form end thrust bearings 12 adapted to hold the shaft longitudinally in its said rotary bearing. 75

A guide for the sliding movement of each leaf-holding member is died up from the cover and comprises two portions; a portion 13 adapted to hold said member against lateral displacement, and other portions 14 80 adapted to hold said member against edge-wise displacement: it will be seen (particularly in Fig. 3) that the direction of the died up bending of one said portion from the cover is opposite to that of the others; 85 whereby said member is held by portions 14 from binding in that part of portion 13, next to the face of the cover.

On cover 1 is pivotally mounted at 16 a swinging arm 17 to which the other end of 90 each leaf-holding member is attached. This arm is held against the slackening movement of said member and close to the face of the cover by a latch 18 pivoted on the cover: when turned to the position of the 95 upper and lower latches in Fig. 1 the latch abuttingly engages its leaf-holding member, as by said member's lug or projection 19 carried thereby and holds it directly against its slackening movement, whereby the strain 100 on the arm's pivots and the tendency to spring the arm by the tension of the leaf-holding member are relieved: but when the latch is swung to the position of the middle latch in Fig. 1, the arm is released and permitted to swing away from the face of the 105 cover to slacken the leaf-holding members for the insertion or removal of leaves from the binder.

The latches may be provided with later- 110

ally extending lugs 50 adapted, when the latches are swung to the position of the upper and lower latches in Fig. 1, to enter died-up keepers 51 in cover 1.

5 A clip 20 (particularly shown in Fig. 2) for adjustably connecting a leaf-holding member to a cross bar as the cross bar 21 of the arm, comprises coöperating parts 22 and 23 disposed on the opposite sides of 10 said member; one of these parts 22 has a socket 28 adapted to receive the cross bar and also a plurality of preferably curved apertures 24 and the other part 23 has a correspondingly-shaped post 25 adapted to 15 be thrust through an opening as 26, in the leaf-holding member and into any of the said apertures. The said parts 22 and 23 are detachably held together with the leaf-holding member between them by a suitable 20 catch 29 pivotally mounted at 27 on one said part. It will be seen that this clip provides a peculiarly secure and strong attachment of the leaf-holding member to the cross bar, and affords a step by step adjustment of such parts relatively to each other.

The invention being intended to be defined solely by the claims, is not to be limited by details of construction shown or described.

30 I claim:

1. In a device of the character described; a pair of covers; a flexible leaf-holding member connecting the covers; and means carried by one cover for holding said members in adjusted position thereon and comprising a rotatable shaft having an eccentric cam adapted in one rotary position of the shaft to engage said member directly and clamp it to said cover.

40 2. In a device of the character described; a flexible leaf-holding member connecting the covers; and means carried by one cover for holding said member in adjusted position thereon, and comprising a rotatable shaft having an eccentric cam adapted in one rotary position of the shaft to clampingly hold said member in its said adjusted position, said shaft having a handle portion adapted in the shaft's clamping position to overlie said member and hold it in parallel relation to the cover at a point other than that of the clamping action.

50 3. In a device of the character described; a pair of covers; a flexible leaf-holding member connecting the covers; and means carried by one cover for holding said members in adjusted position thereon and comprising a rotatable shaft having an eccentric cam adapted in one rotary position of the shaft to engage said member directly and clamp it to said cover, said cam being formed by flattening a portion of the shaft.

40 4. In a device of the character described; a pair of covers; a flexible leaf-holding member connecting the covers; a swinging

70 arm to which said member is attached, and pivoted on one cover; and a latch pivoted on said cover and adapted in one position to abuttingly engage said member and hold the same and the arm against the slackening movement of said member.

5. In a device of the character described; a pair of covers; a flexible leaf-holding member connecting the covers; means rotatably mounted on one cover for holding said member in adjusted position thereon; and rotary bearings for said means died up from 75 said cover and comprising a portion forming the inner side of such bearing, and another portion forming the outer side of such bearing.

6. In a device of the character described; a pair of covers; a flexible leaf-holding member connecting the covers; means carried by one cover for holding said member in adjusted position thereon; a guide on said cover in which said member is adapted to slide longitudinally and comprising a portion died up from the cover and adapted to hold said member against lateral displacement and another portion died up from the cover and adapted to hold said member against edgewise displacement, the direction of its died up bending from the cover being opposite to that of the first mentioned 95 portion.

7. In a device of the character described having a flexible leaf-holding member with an opening therethrough and a cross bar; a clip for adjustably connecting said member to the cross bar comprising coöperating parts disposed on the opposite sides of said member, one of said parts having a socket adapted to receive the cross bar and having a plurality of curved apertures, and the other having a correspondingly-shaped post adapted to be thrust through the opening in the leaf-holding member and into any one of said apertures, and a catch adapted to detachably hold said parts together with 100 said member therebetween.

8. In a device of the character described having a flexible leaf-holding member with an opening therethrough and a cross bar; a clip for adjustably connecting said member to the cross bar comprising coöperating parts disposed on the opposite sides of said member, one of said parts having a socket adapted to receive the cross bar and having a plurality of curved apertures, and the other having a correspondingly-shaped post adapted to be thrust through the opening in the leaf-holding member and into any one of said apertures, and a catch pivotally mounted on one said part and adapted 115 to detachably hold said parts together with said member therebetween.

9. In a device of the character described having a flexible leaf-holding member with an opening therethrough and a cross bar; a 130

clip for adjustably connecting said member to the cross bar comprising coöperating parts disposed on the opposite sides of said member, one of said parts having a socket 5 adapted to receive the cross bar and having a plurality of apertures, and the other having a post adapted to be thrust through the opening in the leaf holding member and into any one of said apertures, and a catch 10 pivotally mounted on one said part and

adapted to detachably hold said parts together with said member therebetween.

In testimony whereof I have hereunto set my hand in presence of subscribing witnesses.
